CONTAINER FOLDING MACHINE

Louis Veyret, Neuilly-sur-Seine, and Georges Gefroy, Paris, France, assignors to La Cellophane, Paris, France, a French company

Application January 20, 1948, Serial No. 3,227
In France October 9, 1944

Section 1, Public Law 690, August 8, 1946
Patent expires October 9, 1964

6 Claims. (Cl. 93—49)

This invention relates to a process and apparatus for folding rectangular water-tight open top containers from flat blanks and more particularly to a process and apparatus for forming liner bags in flat, collapsed form for shipping.

In the manufacture of open top containers or liner bags for the packing of food products, a flat blank of appropriate material, such as paper or a transparent cellulose substance such as cellophane, is folded in such a way that the container is made water-tight up to a certain level without the use of adhesives. Inasmuch as such containers are made of thin, flexible material, they cannot be shipped in formed condition, but must be manufactured in the place where they are to be used. This requires that the user install apparatus for folding and forming the containers, which in many cases restricts their use.

It is an object of the present invention to provide a process and machine for folding containers of the above type in collapsed form so that they may be shipped flat to the point of use.

Another object is to provide a folded container of the above type which may be readily secured to a cardboard box blank for use as a liner.

Another object is to provide a unit comprising a cardboard box blank and a folded water-tight liner which is suitable for shipping and handling by the user.

Although the novel features which are characteristic of this invention are pointed out more particularly in the claims, the nature of the invention will be better understood by referring to the following description, taken in connection with the accompanying drawings, in which specific embodiments thereof have been set forth for purposes of illustration.

In the drawings:

Fig. 1 is a perspective view of the container as it is opened for filling;

Fig. 2 is a detail view illustrating the method of folding the end flaps;

Fig. 3 is a plan view of the completed container as it is delivered from the folding machine in flat collapsed form;

Fig. 4 is a plan view of the cardboard box blank with the folded and collapsed liner secured thereto;

Fig. 5 is a plan view of a portion of the folding mechanism with parts broken away;

Fig. 6 is a longitudinal section taken along the line 6—6 of Fig. 5;

Fig. 7 is a transverse section taken on the line 7—7 of Fig. 5;

Fig. 8 is a plan view similar to Fig. 5 showing

the first folding operation in which the end flap is folded over;

Fig. 9 is a longitudinal section taken along the line 9—9 of Fig. 8;

Fig. 10 is a partial plan view similar to Fig. 8 showing the second folding operation in which one side flap is folded over;

Fig. 11 is a similar plan view showing the third folding operation in which both side flaps are folded over;

Fig. 12 is a similar plan view showing the completed fold with the folding members retracted;

Fig. 13 is a section taken along the line 13—13 of Fig. 12 illustrating the position of the sealing head;

Fig. 14 is a plan view of the folding mechanism showing the folding members of one end retracted and the folding members in place for effecting the folds at the other end of the container;

Fig. 15 is a section through the base plate, taken on the line 15—15 of Fig. 7, showing the suction chambers;

Fig. 16 is a side elevation of an automatic folding machine embodying the invention with parts

broken away and with the sealing mechanism removed for clarity;

Fig. 17 is a top plan view thereof;

Fig. 18 is a detail view of the operating mechanism for the flap folding shutters;

Fig. 19 is a detail view of the cam mechanism; and Fig. 20 is a diagrammatic view illustrating the operation of the sealing mechanism.

Referring to the drawings more in detail, Fig. 1 shows the liner bag of rectangular form and open top which has been opened for use. This bag comprises side walls 10, bottom 11 and ends formed by bottom end flaps 13 and side end flaps 14 and 15 which overlap to form end seams 16 which may be sealed by a suitable adhesive. The folded bag is tight to the top edge 12 of the bottom flaps 13 and in use is filled to that level, the remainder of the ends and sides being folded over to close the top of the package.

Fig. 2 illustrates the method of folding a flat blank A to form the end flaps above mentioned. In this method of folding one end of the flat sheet is first folded over about a fold line 17 to form the bottom end flap 13. Thereafter the two side flaps 14 and 15 are folded over about fold lines 18 and 19 respectively which extend at an angle of approximately 45° with the side edges 20 of the flat blank. The flaps 14 and 15 are folded flat against the flap 13 to form inner fold lines 21 and 22 which extend at an angle of about 45° to the fold line 12. After

folding, the flaps 14 and 15 overlap to form seams 16 which are sealed by a strip of adhesive 23 which, in the case of a cellophane bag, may comprise a thermoplastic adhesive. The other end of the bag is then formed in a similar manner by folding about lines which are designated by similar reference characters with the suffix "a" (Fig. 3) to provide a flat, collapsed bag which can be readily opened to the form shown in Fig. 1 by lifting the two folded ends upwardly and smoothing out the folds 18, 18a, 19 and 19a on the two side walls of the bag.

The completed and collapsed bag is attached to a cardboard blank 25 having a bottom panel 26, end panels 27 and 28, side panels 29 and 30, and a top panel 31, as shown in Fig. 4. Preferably the bottom of the bag may be attached by a peripheral band of adhesive 32 to the bottom panel 26 of the box blank and the flat portion of the sides of the bag may be attached by adhesive 33 to cause the collapsed bag to lie flat with the box blank, but to be opened up into rectangular form for use as shown in Fig. 1 when the blank is folded into the form of an open box. In this way the user has only one handling operation to perform for opening the box, and the cardboard box and water-tight liner comprises a single unit.

The various folding operations above described may be effected by the mechanism illustrated in Figs. 5 to 15. The mechanism includes a flat rectangular table 40 having a shape to receive the blank A of material to be folded. The table 40 is provided on its upper surface with a plurality of suction chambers 42 to 46 as indicated in Fig. 15 which are adapted to hold the unfolded portion of the blank flat against the table during the successive folding operations. At its upper surface the table is provided with a plurality of suction openings 50 (Fig. 5) communicating with the suction chambers for the above purpose.

A plate 51 of trapezoidal form having an edge 52 corresponding to the end fold 17 of the bag and with edges 54 inclined at 45° to correspond to the side folds 18 and 19 is positioned above the table 40 and is mounted on rods 55 by which it may be shifted from the position shown in Fig. 5 over the table 40 to the position shown in Fig. 14 where it is retracted from the table 40.

A pair of shutters 56 and 57 are mounted on rods 58 and 59 respectively and are adapted to be shifted independently of the plate 51 from an advanced position as shown in Fig. 5 to a retracted position as shown in Fig. 12. The shutters are provided at their forward ends with edges 60 and 61 which are inclined by an angle of 45° to the axis of the rods 58 and 59 and conform to the fold lines 21 and 22 of the blank. The shutters 56 and 57 may be rotated from an upstanding position, as shown in Figs. 5 and 8, to a position flat against the plate 51, as shown in Figs. 11 and 12. The table 40 is provided at one end with a rectangular opening 63 in which is secured a rectangular slide 69 having an edge 70 conforming to the bottom fold line 17. The slide 69 is mounted by means not shown for sliding movement over the face of the table 40 and is provided with an actuating tab 72 engaging a stationary cam 73 carried by the table 40 for elevating the slide as it is shifted forwardly so as to lift the same above the plane of the blank A and the plate 51 to thereby initiate the folding of the bottom tab 13 about the fold line 17. The suction chambers 42 to 46 are connected to suitable sources of suction and may be controlled

as desired in accordance with the successive folding operations so as to connect the various chambers to suction or to atmosphere. The area of the central compartment 46 corresponds to the area of the finished bag in its flatly folded form.

The above described elements are adapted to fold the flaps at one end of the blank. Similar elements are provided for folding the other end of the bag, indicated in Fig. 14 by the slide 69a, shutters 56a, 57a, and plate 51a.

For sealing the end seams 16 and 16a of the bag when the material is heat-sealable or is provided with a thermoplastic adhesive, a sealing head 75 (Fig. 13) is provided having a sealing face in the form of a Y as indicated in the dotted lines in Fig. 12 conforming to the longitudinally extending seam 16 and the folds 21 and 22. The sealing head 75 is arranged above the table 40 and is adapted to be brought into engagement with the folded bags at the proper time for sealing the various folds. Inasmuch as the folds for the two ends are overlapped as indicated in Fig. 14, the heating member is reversed in position at alternate actuations so as to register with the respective end folds. In the event that a heat sealing adhesive is used the head 75 is provided with heating means. For other types of adhesive, the sealing head will be modified accordingly so as to effect the necessary sealing operation.

In the operation of the elements shown in Figs. 5 to 15 the plate 51 and shutters 56 and 57 are first retracted in the position indicated in Fig. 14 and the corresponding elements 51a, 56a and 57a are retracted onto the other side of the table. Suction is then applied to the chambers 42 to 46 and a blank A is placed flat on the table 40. The plate 51 is then advanced and laid flat over the blank A with the edge 52 thereof registering with the fold line 17 of the blank as indicated in Fig. 5. The shutters 56 and 57 are then advanced into corresponding position with their ends registering with the edge 52 of the plate 51 and with their edges 60 and 61 lying in a vertical plane.

For the first folding step, the suction is cut off from the chambers 42 and 43 and the slide 69 is pushed inwardly (to the right in Figs. 5, 6, 8 and 9). As the slide 69 is pushed inwardly the lug 72 thereof riding over the stationary cam 73 elevates the slide thereby lifting the overlying portion of the blank A and starting a fold at the line 17. As the slide 69 is pushed inwardly over the top of the plate 51, the bottom flap 13 is folded down against and about the edge 52 of the plate 51 as indicated in Figs. 8 and 9, with the side folds 14 and 15 extending loosely over the shutters 56 and 57.

For the next operation, the shutter 56 is rotated 90° about its axis and is caused to lie flat over the slide 69 as indicated in Fig. 10. This results in folding the flap 15 down against the blank and forming the fold lines 19 and 21.

In the third stage of the folding operation, the shutter 57 is rotated 90° about its axis and is caused to lie flat over the slide 69 as indicated in Fig. 11 thereby folding the flap 14 down against the blank and forming the fold lines 18 and 20. The end flaps are now completely folded and require sealing.

The slide 69 and shutters 56 and 57 are now retracted as indicated in Fig. 12 leaving the end folds lying flat against the top of the plate 51. The sealing head 75 is then brought downwardly against the overlapping folds for sealing the same,

the plate 51 separating the folded flaps from the remainder of the blank during the sealing operation. The plate 51 is then retracted to the position shown in Fig. 14. The corresponding elements 51a, 56a, 57a and 69a are then actuated from the opposite end of the table 40 for folding over the opposite end folds which are then sealed in the manner above described. During this portion of the folding operation the suction is cut off from the chambers 44 and 45 to release the corresponding portions of the blank for folding over. The blank then remains on the table 40 and is held by the suction of the chamber 46 which corresponds in area to the folded blank. Suction to this chamber is then released and the folded blank removed, after which it may be applied to a box blank if desired as indicated in Fig. 4, or may be shipped in a flat, folded, collapsed condition.

Figs. 16 to 20 show the operating mechanism for a semi-automatic machine for effecting the above-described operation. In this embodiment, the table 40 and other operating parts are mounted on a frame 79. Ducts 80, 81 and 82 connect the various suction chambers 42 to 45 in the table 40 to a rotary valve 83 which is actuated by a vertical drive shaft 84 for connecting the respective ducts 80 to 82 to suction or venting the same at the appropriate points in the operating cycle. The shaft 84 carries a driving gear 84a which is driven by any suitable means such as a motor not shown.

The plates 51 and 51a are mounted on brackets 85 and 85a attached to slides 86 and 86a respectively which are mounted to slide on guide rods 87. The slides 86 and 86a are actuated by levers 88 and 88a (Figs. 16 and 19) pivoted at 90 and 90a respectively to the frame 79 and connected at their lower ends by links 91 and 91a to slides 92 and 92a which slide in stationary sleeves 93 and 93a and carry followers 94 and 94a respectively engaging the surface of a cam 95 which is driven by the shaft 84. Springs 96 and 96a serve to hold the followers 94 and 94a respectively against the cam 95.

The plates 51 and 51a are flexible and are adapted to rest upon the blank A on the table 40 for holding the blank firmly in place during the folding operations. In order to lift the plates so as to permit the same to pass over the blank A as the plates are advanced, bell crank levers 100 and 100a are provided which are pivoted about pins 101 and 101a secured in a fixed bracket (not shown) and are normally held in retracted position by springs 102 and 102a (Fig. 17). Arms 103 and 103a, rigidly attached to the slides 86 and 86a, are adapted to engage the levers 100 and 100a for rocking the same to elevate the plates 51 and 51a when the slides are advanced. After the plates have passed the respective levers 100 and 100a the levers are retracted by the springs 102 and 102a and the plates rest flat upon the blank A in the position shown by plate 51 in Fig. 16.

The slides 69 and 69a are actuated by arms 105 and 105a attached to cranks 106 and 106a which are driven by shafts 107 and 107a. The shafts 107 and 107a carry arms 108 and 108a at their lower ends which carry followers 109 and 109a positioned to engage a cam 110 (Figs. 16 and 19).

The cam 110 serves to rock the arms 108, 108a and the cranks 106, 106a for advancing and retracting the slides 69, 69a at suitable times during the cycle of operation.

The shutters 56 and 57 are mounted on car-

riages 115, as shown in detail in Fig. 18, which slide on rods 117. The shutters are formed integrally with rods 120 which are journalled for rotation in the brackets 115 but are held against sliding in the brackets 115 by collars 120'. At their rear ends the shafts 120 are formed with helical slots 121. A bracket 122 joins the shutters 56 and 57 on each end of the machine and is normally held in a rearward position on the respective shafts 120 by means of springs 123. The bracket 122 is provided with pins engaging the helical slots 121 in the shafts 120 so as to rotate the respective shutters due to axial movement of the shafts 120 within the bracket 122. In fully retracted position the bracket 122 engages a stop 125 attached to the frame. Further movement of the bracket 115 to the right (Fig. 18) then causes the spring 123 to compress and, due to the helical groove 121, rotates the shutter to upstanding position as shown. In this position it is engaged by a latch 126 which locks the same against rotation until the latch is released. The bracket 115 is driven by an arm 127 pivoted at 128 to the frame and attached at its lower end by a link 129 to a slide 130 which is mounted to slide in a stationary sleeve 131 on the frame 79 and carries a follower 132 which engages the cam 95 and is actuated thereby. A spring (not shown) normally holds the follower 132 against the cam 95. A suitable linkage actuated by the cam shaft 84 also releases the latches 126 in proper sequence for allowing the shutters 56 and 57 to rotate for folding the flaps against the plate 51 as above described. The spring 123 is connected to rotate the shutters to folded position. Similar mechanism actuates the shutters 56a and 57a and has been given corresponding reference characters with the suffix "a".

The sealing band 75 is mounted on a shaft 135 which is positioned to slide within a supporting bracket 136 attached to the frame 79. The shaft 135 is normally held retracted by a spring 137 and is actuated by a lever 140 (Fig. 20) pivoted to the frame at 141 and connected by a link 142 to a lever 143 which is pivoted to the frame at 144 and carries a follower 146 engaging the cam surface 147 of a vertical cam 148 attached to and driven by the cam shaft 84. A spring 149 serves to hold the follower 146 in engagement with the cam surface. The shaft 135 is rotated 180° on each upstroke by means of a pin carried by the bracket 136 and engaging helical grooves 150 and an axial groove 151 in the shaft 135. The arrangement is such that on the down stroke the pin engages the axial groove 151 and on the up stroke engages the helical groove 150 for causing 180° rotation of the shaft 135 so as to bring the sealing head 75 in position to successively seal the opposite folds of the formed bag. The follower 146 and control linkages for the head 75 are omitted from Fig. 16 for clarity.

It will be noted that in the semi-automatic machine shown in Figs. 16 to 20, the cam shaft 84 is driven by any suitable means, such as a driving motor (not shown), and upon each rotation of the shaft 84 the various cam followers 94, 109 and 132 are operated in sequence to effect the successive folding operation. The follower 94 first advances the plate 51 into position over the blank A and the follower 132 advances the shutters 56 and 57 into folding position. The valve 83 is then shifted to break the suction to the chambers 42 and 43 and the follower 104 is actuated to shift the slide 69 over the plate 51.

so as to initiate the bottom fold 13 on the left side of the bag. The slide 69 is then retracted and shutters successively released for folding over the flaps 14 and 15 as previously described, after which the elements are retracted by their respective cam followers and the operation repeated from the opposite end of the machine so as to form the opposite end folds. The suction to the chamber 46 is then cut off to release the folded bag. After each folding operation the cam follower 146 is actuated to advance the sealing head 75 to seal the folded ends of the bag. The suction to the chamber 46 is finally shut off to allow the completed bag to be removed from the machine.

It is obvious that the various details of construction are shown merely for purposes of illustration and that various changes and modifications may be made therein as will be readily apparent to a person skilled in the art. The machine may be made completely automatic by including a device for feeding blanks to the table 40, for example from a continuous roll provided with knives timed to cut off blanks of suitable size. A plurality of such machines may be mounted around the periphery of a drum having an intermittent rotary motion and fed from a spool of strip material, or a pair of machines may be placed side-by-side or end-to-end and synchronized for operation by a single operator. The machine may be timed to operate alternately so that the operator can feed blanks to one machine during the folding cycle of the other machine. Various other changes and modifications will be apparent to a person skilled in the art. The invention is only to be restricted according to the scope of the following claims.

What is claimed is:

1. An apparatus for forming folded open top cartons which are tight to a predetermined level from flat rectangular blanks, comprising a perforated table to receive said blank, suction compartments conforming in shape to the successive parts of the blank to be folded and communicating with said perforations, a flat plate of trapezoidal form having a straight front edge conforming to the width of the carton and having outwardly flaring side edges, means mounting said plate to slide over the blank on said table, a slide mounted beneath said blank and in advance of the front edge of said plate, cam means to raise said slide and slide the same over said plate to form a front fold in said blank, a pair of slidable shutters disposed above said plate and having flaring outer edges, means successively rotating said shutters over said plate to form side folds over said front fold, means retracting said shutters and said slide after said folding operation, a Y-shaped heating member positioned over said plate to register with the edges of the side folds and means for moving said heating member into engagement with said folded blank for sealing said folds.

5 2. An apparatus for forming folded open top cartons which are tight to a predetermined level from flat rectangular blanks, comprising a perforated table to receive said blank, suction compartments conforming in shape to the successive parts of the blank to be folded and communicating with said perforations, a flat plate of trapezoidal form having a straight front edge conforming to the width of the carton and having outwardly flaring side edges, means mounting said plate to slide over the blank on said table, a slide mounted beneath said blank and in advance of the front edge of said plate, cam means to raise said slide and slide the same over said plate to form a front fold in said blank, a pair of slidable shutters disposed above said plate and having flaring outer edges, means successively rotating said shutters over said plate to form side folds over said front fold, means retracting said shutters and said slide after said folding operation, a Y-shaped heating member positioned over said plate to register with the edges of the side folds and means for moving said heating member into engagement with said folded blank for sealing said folds, valve means for successively releasing the suction in the compartments registering with the successive folds, and means retracting said plate from the folded blank while maintaining suction to retain the folded blank on said table.

20 3. In an apparatus as set forth in claim 1 cam means actuated in sequence to control said plate, slide and shutters.

25 4. In an apparatus as set forth in claim 1 rods carrying said shutters, bearings in which said rods are mounted for sliding and rotation, helical means on said rods to rotate the same in response to sliding movement and cam means to slide said rods in said bearings.

30 5. An apparatus as set forth in claim 1 having duplicate plate, slide and shutters at both ends and means for operating the second set of elements in succession after one end of said blank has been folded.

35 45 6. In the apparatus set forth in claim 5 means for rotating said sealing head 180° after each actuation thereof for successively sealing the folds at each end.
